UNITED STATES PATENT OFFICE

2,169,808

ELECTRIC FURNACE AND ELECTRODE
MECHANISM THEREFORWilliam E. Moore, Pittsburgh, Pa., assignor to
Pittsburgh Research Corporation, Pittsburgh,
Pa.Original application January 31, 1936, Serial No.
61,810. Divided and this application January
11, 1937, Serial No. 120,060

6 Claims. (CL 13—14)

The present invention relates to improvements in furnaces and more particularly to electric furnaces of the type used in metallurgical operations although not necessarily restricted to this use.

An important object of this invention is the provision of an electric furnace for metallurgical operations which can be made in any size or capacity but which is particularly well adapted for the smaller capacity furnaces, being inexpensive to produce and to operate. Small furnaces of this type having a capacity of one-half to one and a half tons, for example, can be run at a very low demand cost whereas large furnaces require a large demand cost when operated at low tonnages in times of reduced output. The furnace of the present invention may be made in small sizes to be operated in conjunction with a large furnace, as a bleeder unit or for operation with its own substation as a separate melting furnace.

Another object of this invention is the provision of an electric furnace which takes up a minimum of space, which is easily operated, strong and durable, and which is economical in operation.

Other objects and advantages of this invention will be apparent during the course of the following description.

This application is a division of my co-pending application No. 61,810 filed January 31, 1936 for Electric furnaces.

In the accompanying drawings, which form a part of this specification and wherein like characters of reference denote like parts throughout;

Figure 1 is an elevation of a furnace embodying this invention,

Figure 2 is a top plan view of the furnace,

Figure 3 is a side elevation of the electrode supporting column, parts being broken away,

Figure 4 is an end elevation of one of the swiveling cuffs connecting an electrode arm to one of the electrode supporting columns,

Figure 5 is a side elevation thereof,

Figure 6 is a side elevation of a modified form of one of the electrode supporting columns in position on the furnace and showing the hoisting gear in place,

Figure 7 is an elevation of the hoisting gear at right angles to Figure 6, parts being broken away,

Figure 8 is a top plan view of the hoisting reel and guide roller of Figure 6 showing their positions with respect to the electrode supporting column which is shown in section.

Figure 9 is a longitudinal sectional view of one of the guide rollers.

Figure 10 is a side elevation of an eccentric shaft for adjusting the guide roller,

Figure 11 is an end elevation thereof on a somewhat larger scale, and,

Figure 12 is a side elevation of one of the electrode columns showing another position of the hoisting mechanism with respect thereto.

In the accompanying drawings, wherein for the purpose of illustration is shown a preferred embodiment of this invention, the numeral 15 designates the crucible shell of a furnace embodying this invention. This shell may be of plate steel and cylindrical in shape with a flat bottom 16 15 also of plate steel welded to the inner wall of the shell. A bezel ring 17 surrounds the top of the furnace shell to strengthen the shell. A door 18 and a tapping spout 19 permit operation of the furnace and inspection of the interior of the crucible, and a tilting mechanism 20, which may be power or hand operated, is arranged to tilt the crucible on suitable runners and rockers 21.

The roof of the furnace comprises a metal flanged roof ring 22 supporting a refractory arched roof 23. The roof is removably arranged on the furnace crucible and may be lifted by means of suitable loops 24 arranged at the top of ring 22. Four brackets 25 are secured to the top of the bezel ring 17 and are each provided with a centering bolt 26 to engage the outer periphery of the roof ring. By adjusting the bolts 26 the furnace roof may be properly centered in place upon the top of the crucible.

The electrodes 27 are carried by suitable water cooled clamps 28 of electrically conducting material such as copper. Water circulating pipes 29 carry cooling water to and from the clamps 28.

The electrode arm 30 is preferably in the form of an H-beam. The arm 30 may be of any other desired cross-section and if desired, may be of electrically conducting material such as copper or brass. It is preferred, however, to form the arm of steel to give the necessary strength for carrying the electrode, and to reinforce the arm 40 with copper or other electrically conducting bars 31 placed within the flanges of the arm and bolted thereto. The electric current is conducted to the clamps 28 by bars 31.

Electrode columns 32 are arranged to be raised 60 and lowered, and support the electrode arms 30, being insulated therefrom. The columns may be of any suitable cross-section such as a simple H-beam, or the H-beam may be boxed in, as indicated in Figure 8, for greater strength. A rec- 55

tangular platform 33 is arranged at the top of each column 32 and is supported in a horizontal position by diagonal brace 34. A sleeve 35 is rigidly secured transversely of the lower side of the platform 33 centrally thereof and projects a slight distance beyond the side edges of the platform as indicated in Figure 4. A pair of set screws 36 is arranged at each end of the platform 33 for a purpose to be hereinafter described. A substantially inverted U-shaped hood 37 has thickened lower edges provided with central openings to receive a pivot pin 38 adapted to extend through sleeve 35 and to be secured by means of cotter keys 39 or the like. The hood is pivotally secured to the platform 33 by means of pivot pin 38.

The arm 30 is adapted to extend through the pivoted hood 37 and is insulated and spaced from the hood and from the platform 33 by means of insulating strips 40 of asbestos or the like and pieces 41 of suitable board such as ebony board, as shown in Figure 4. Additional boards or strips of wood or other suitable material may be arranged above or below the arm 30 and insulating material or at the sides thereof to fill up any space between the insulating material and the walls of the hood, if desired. By tightening up on bolts or set screws 36 the arm 30 is securely clamped in the hood. The pivoted hood 37 assures a rigid clamping of the arm to the platform 33. The bars 31 extend beyond hood 37 and are connected to a source of electric current by suitable conductors 31'. By using the pivoted hood 37 and screws 36, the arm is forced into intimate engagement with the top of the hood. Due to the pivoting of hood 37, it will be adjusted to the position of arm 30, so that the arm will engage the hood throughout the entire length of the hood. This engagement is not dependent upon the proper setting of the screws 36 but results from the pivoted mounting of the hood and the position of the screws 36 on the platform or column. While the screws 36 control the angular position of arm 30, the proper relation of the hood and arm is assured by the pivotal mounting of the hood irrespective of the setting of the screws 36.

The columns 32 are each adjustable vertically to raise and lower the electrodes, and are guided by suitable rollers 42 and 42' supported by upper and lower brackets 43 secured to the furnace shell 15. Each of the rollers comprises a pair of adjustably spaced roller members 44 held apart by the column 32 and rotatably mounted on shaft 45 which in turn is secured to suitable brackets 46 by adjusting nuts 47 and set screws 48, as indicated in Figure 9. The roller bearings 49 may be provided to reduce friction. The rollers 42' which are mounted on opposite sides of the columns 32 are preferably adjustable transversely of the roller axis, as well as longitudinally thereof. The transverse adjustment may be obtained by forming the roller shaft 45' with an eccentric body portion 50 to receive the roller members 44 as shown in Figures 10 and 11. Adjustment of the roller members toward and away from the columns is effected by rotating shaft 45'.

The vertical adjustment of columns 32 is preferably effected by electric winches which are preferably mounted on the lower of the brackets 43 which is the coolest position for the winches and one which places them out of the operator's way. If desired, however, these winches may be located on the upper of the brackets 43, as indicated in Figure 12. Each of the winches consists of a worm-gear casing 51 provided with a central

shaft 52 on which a worm gear 53 is mounted. A worm 54 engages worm gear 53 and is mounted on a horizontal shaft 54' arranged at a right angle to shaft 52 and which extends through the casing 51. A relatively large gear wheel 55 is 5 mounted to turn with the worm shaft 54' exteriorly of the casing 51. A small pinion gear 56 meshes with large gear 55 to rotate the large gear and is in turn operated by a suitable electric motor 57 mounted on a platform 58 which may be 10 formed integrally with the top of casing 51. A suitable handle 59 may be connected to the large gear wheel 55 for manual rotation thereof.

Worm gear shaft 52 extends outwardly beyond casing 51 in which it is journaled and passes in 15 proximity to column 32. A suitable reel 60 is mounted on shaft 52 to turn therewith and a cable 61 is wound on reel 60 and is connected at its end to the lower end of column 32 as indicated in Figure 6. Preferably reel 60 is arranged in 20 contact with the column and has its sides provided with radially extending annular flanges 62 adapted to extend past the edges of column 32 so that reel 60 serves as a roller to engage the column, as indicated in Figures 6, 7 and 8. 25

The winch motors 57 are preferably used for raising and lowering the electrode columns, but this movement may also be effected by use of the hand crank 59. The reel 60 serves in the dual capacity of reel and column roller, while the rollers may be adjusted toward and away from the columns by means of the eccentric shafts 50. The reels 60 may be used in conjunction with the usual rollers and engage the side edges of the columns, as shown in Figures 1 and 2. It is preferred, however, to arrange the reels as shown in Figures 6, 7, 8 and 12 to take the place of one of the rollers on each column and engage and guide the rear edge of the column. In this position, the reels and winches are disposed at an 40 angle of 90 degrees from the position shown in Figures 1 and 2.

The use of the pivoted cuffs 37 assures a secure connection between arms 30 and columns 32 while the set screws 26 permit a ready adjustment and centering of the roof. The columns 32 and winch mechanism are supported by the furnace shell and tilt therewith, while the winch construction employed dispenses with the necessity for numerous pulleys for operating the 50 electrodes.

While the preferred embodiment of the invention has been shown and described, it is to be understood that various changes in the size, shape and arrangement of parts may be resorted to without departing from the spirit of the invention or the scope of the subjoined claims. 55

Having thus described my invention, what I claim and desire to protect by Letters Patent is:

1. In a furnace of the character described, a furnace crucible, an electrode extending into said crucible, an electrode arm to support said electrode, a column carried by the crucible, a platform at the top of said column and adapted to support said electrode arm, a hood pivotally connected to the column and extending over the electrode arm, a clamping member carried by the platform and adapted to clamp the arm against the pivoted hood, and means to insulate the arm from the platform and hood. 60

2. In a furnace of the character described, a furnace crucible, an electrode extending into said crucible, an electrode arm to support said electrode, a bracket supported by the furnace crucible, a column slidably engaging said bracket and 70

5 operatively engaging said electrode arm to raise and lower the arm and electrode, a column raising and lowering mechanism operatively engaging said column and supported by said bracket, said raising and lowering mechanism comprising a drum, a cable wound on the drum and secured to the column, and an electric motor operatively connected to the drum, said drum having an annular portion arranged in contact with the 10 column to serve as a guide roller therefor.

10 3. In a furnace of the character described, a furnace crucible, an electrode extending into said crucible, an electrode arm to support said electrode, a bracket supported by the furnace crucible, a column secured to said electrode arm, a 15 guide member carried by the bracket and engaging one side of said column, a rotatable reel supported by said bracket and having a guide portion engaging the opposite side of said column, 20 means carried by said reel and operatively engaging the column to raise and lower the column when the reel is rotated, and means to rotate said reel.

25 4. In a furnace of the character described, a furnace crucible, an electrode extending into said crucible, an electrode arm to support said electrode, a bracket supported by the furnace crucible, a column secured to said electrode arm, a 30 guide member carried by the bracket and engaging one side of said column, a rotatable reel supported by said bracket and having a guide

portion engaging the opposite side of said column, means carried by said reel and operatively engaging the column to raise and lower the column when the reel is rotated, and means to rotate said reel, said guide member being adjustable 5 toward and away from the column.

5 5. In a furnace of the character described, a furnace crucible, an electrode extending into said crucible, an electrode supporting column, a bracket carried by said furnace crucible, a reel 10 supported by said bracket and carrying a member to engage the column and raise and lower the column when the reel is rotated, an annular guide member carried by said reel and engaging the column, means to rotate the reel, and a roller 15 carried by said bracket and engaging the column on the opposite side thereof.

6. In a furnace of the character described, a furnace crucible, an electrode extending into said crucible, an electrode supporting column, a 20 bracket carried by said furnace crucible, a reel supported by said bracket and carrying a member to engage the column and raise and lower the column when the reel is rotated, an annular guide member carried by said reel and engaging the 25 column, means to rotate the reel, and a roller carried by said bracket and engaging the column on the opposite side thereof, said roller being adjustable toward and away from the column.

30

WILLIAM E. MOORE.
